BENCH VISE

Carl S. Carlstrom, Waltham, Mass., assignor to R. S. Wilder Incorporated, Waltham, Mass., a corporation of Massachusetts

Application May 15, 1958, Serial No. 50,894

Term of patent 14 years

(Cl. D54—13)

Fig. 2

Fig. 1

Fig. 3

Fig. 1 is a side elevational view of a bench vise, embodying my new design;

Fig. 2 is an end view in elevation; and

Fig. 3 is a top view.

The essential features of my design reside in those portions shown in full lines.

I claim:

The ornamental design for a bench vise, substantially as shown and described.
